Primary Examiner—Cathron C Brooks*Assistant Examiner*—Kevin K Rudzinski(74) *Attorney, Agent, or Firm*—Frank R. Nirajan(57) **CLAIM**

The ornamental design for an LED lens, as shown and described.

DESCRIPTION

FIG. 1 is a perspective view of an LED lens showing our new design.

FIG. 2 is a front elevational view thereof, the rear elevational view being a mirror image of FIG. 2.

FIG. 3 is a left-side, elevational view thereof, the right-side, elevational view being a mirror image of FIG. 3.

FIG. 4 is a top plan view thereof.

FIG. 5 is a bottom plan view thereof; and,

FIG. 6 is a cross-sectional view thereof, taken along line VI—VI of FIG. 1.
